A. A. QUICK

HAULING OR STRAINING DEVICE

Filed Nov. 20, 1920

UNITED STATES PATENT OFFICE.

ALFRED ARTHUR QUICK, OF THORNBURY, VICTORIA, AUSTRALIA, ASSIGNOR TO THE QUICK ENGINEERING COMPANY, PROPRIETARY LIMITED, OF THORNBURY, VICTORIA, AUSTRALIA.

HAULING OR STRAINING DEVICE.

Application filed November 20, 1920. Serial No. 425,382.

To all whom it may concern:

Be it known that ALFRED ARTHUR QUICK, subject of the King of Great Britain, residing at 75 Penders Street, Thornbury, in the State of Victoria, Commonwealth of Australia, engineer, has invented certain new and useful Improvements in Hauling or Straining Devices, of which the following is a specification.

10 This invention relates to improvements in hauling and straining devices and refers especially to a device the employment of which enables a comparatively long length of rope or like flexible member to be operated upon 15 without having to provide a winding drum capable of accommodating the whole length of the rope hauled.

The invention is directed to the provision of an economically constructed and comparatively light and powerful hauling and straining device which will be particularly adaptable for the purpose of pulling down trees and uprooting stumps in land clearing operations although it will be found highly 25 efficient for other hauling purposes or where heavy weights have to be raised or moved from one place to another.

More particularly the invention is directed to the provision of improvements in that 30 class of hauling and straining devices wherein the load is maintained on a rope having frictional contact with a lever operated winch and a pair of pulleys and the necessary strain or tension on the rope for maintaining said frictional contact is applied by 35 the load itself in due proportion both to that portion paying on to the winch as well as to that portion paying off from the winch.

The object of the present invention is to 40 provide means in this class of hauling and straining device whereby a good frictional contact will be ensured between the rope and the winch when a load is applied to the said rope and whereby the rope and operating 45 lever are arranged in such a way that the latter can be operated to impart a hauling movement to the load both in its backward and forward movements.

I accomplish the abovementioned object by 50 providing a hauling and straining device comprising a winding drum an oscillating lever and pawl and ratchet mechanism for intermittently operating the winding drum,

and a hauling rope connected to the lever at a point distant from the centre thereof less 55 than the radius of the winding drum and adapted to pass around one or more pulleys on to the winding drum constructed and arranged whereby each of the backward and forward movements of the operating lever 60 actuates the device to impart a strain to the hauling rope and a movement to a load attached thereto.

In order that the invention may be more readily understood reference will now be 65 had to the accompanying sheet of explanatory drawings, wherein:

Figure 1 is a view in side elevation of a hauling or straining device constructed in accordance with the present invention and 70 illustrates its application to the purpose of pulling down trees.

Figure 2 is a perspective view of the winch showing part of an anchor rope and part of a hauling rope connected thereto. 75

Figure 3 is a view in perspective of part of the operating lever and pawls connected thereto.

Figure 4 is a view in side elevation of a modified form of winch showing means for 80 actuating the same by the aid of animal power.

Figure 5 is a view in perspective of the winding drum of the winch and shows means for applying the "liner" of soft metal to the 85 rope groove of the same.

Figure 6 is a view in side elevation of a slightly modified form of hauling and straining device.

In these drawings like characters of reference have been employed to indicate the same or corresponding parts throughout the several views and the letter *a* designates the frame of the winch having a winding drum *b* mounted on an axle *c* at its forward end 95 and an anchor rope *d* connected to its rear end.

The winding drum is formed with a rope groove *e* and the flanges on both sides thereof are formed with ratchet teeth *f* of approved design.

An operating lever *g* having a bifurcated end is pivoted to the ends of the axle *c* and within the bifurcation of the said lever is pivoted a pair of pawls *h* which are 105 adapted to engage with the teeth of the

ratchets on the winding drum on the forward movement of the lever. The pawls *h* are normally kept pressed against the ratchet teeth by means of a spring *i* and a hook *j* on the lever is adapted to engage a bar *k* connecting the said pawls when the same are lifted in order to retain them in their disengaged positions.

A second pair of pawls *l* is pivotel to the frame of the winch and these pawls are adapted to retain the winding drum in position against any tendency it may have to move backward when the device is in use.

The pawls *l* are normally kept pressed against the ratchet teeth on the winding drum by a spring *m* and they can be held out of engagement with the said ratchet teeth by means of a hook *n* and connecting bar *o* as hereinbefore described with reference to the pawls on the operating lever.

The pawls *h* and *l* are held in their inoperative positions by the hooks *j* and *n* when it is desired to fleet the hauling rope *t*, the winding drum being then free to rotate in both directions.

In some instances it may be advisable to prevent the axle *c* rotating with the winding drum and this can be effected by passing a pin *p* through a hole in the end of the said axle and securing the said pin to the frame of the winch as shown in Figures 2 and 4 of the drawings or by any other approved means.

A link *q* is pivoted at one end to the lever *g* at a point distance from the pivot centre thereof equal to one half the radius of the pitch of the rope groove of the winding drum and the opposite end of the said link is provided with a hook *r* or adjustable gripping device *s* for engaging the hauling rope *t*.

One end of the hauling rope *t* is connected to the frame of a snatch block *u* and passes therefrom to and around a second snatch block *v* thence to and around the winding drum *b*, to and around the first snatch block *u* and when pulled taut is hitched to the hook *r* or is engaged by the gripping device *s*.

The frame of the second snatch block *v* may be provided with a roller *w* around which is looped a rope *x* connected to the load to be moved and a similar roller *w'* is connected to the frame of the winch to engage the looped anchor rope *d* as shown in Figure 1.

When the anchor and load ropes are made of hemp or like soft material the rollers *w* and *w'* permit of the strain to be equalized on both sides of the loops thereof, and when the hauling rope is made of the same material it can be readily secured to the hook *r* by means of a "Blackwell" hitch or in any other approved way.

When the anchor and load ropes are made

of steel wire one of their ends can be fixedly or detachably connected to the frame of the winch and to the frame of the second snatch block in any approved way and their other ends can be provided with hooks *y* as shown in Figure 2.

The gripping device *s* is employed more particularly when the hauling rope is made of steel wire and the said gripping device is connected to each side of the bifurcated end of the operating lever by means of double links *q*.

The groove *e* of the winding drum *b* is preferably formed with inclined sides and the bottom thereof is provided with a liner *e'* of lead or other suitable alloy or soft material and the object of this soft liner is to provide a good frictional grip for the hauling rope and it also serves to prevent excessive wear on the same. The rope grooves in the snatch blocks *u* and *v* also can be provided with a liner of lead or other suitable material to ensure a soft bed for the rope passing around the same.

The operating lever for the winch can be actuated by hand or by animal or motive power. In Figure 4 where I have shown a winch fitted with means for operating the lever from a source of power the frame is extended to provide room for the free operation of a pair of connecting links *A* having their forward ends pivoted to the operating lever and their rear ends mounted on eccentrics *B* formed on or fitted to a spindle *C* passing through the frame of the winch.

The eccentrics *B* can be formed integrally with or they can be fitted rigidly to a rope pulley *D* mounted concentrically on the spindle *C*. A pair of links *E* is pivoted to the ends of the spindle *C* and the lower or depending ends of these links are shaped to carry a pair of grooved rollers *F*.

A second pair of links *G* is pivoted to the lower ends of the links *E* midway between the rollers *F* and the lower ends of these links support a grooved roller *H*. The length of the links *G* and the size of the roller *H* and the size of the rollers *F* are such that when the said links are swung forward or rearward the roller *H* will move close to one or other of the rollers *F*.

A rope *I* is looped around the rope pulley *D* and its ends are passed between the rollers *F* and on opposite sides of the roller *H* as shown in Figure 4. The ends of the rope *I* can be formed with eyes *J* or fitted with hooks or other means for connecting them to animal draught gear (not shown).

In order to operate the winch by animal power one end of the rope *I* is connected to the draught gear of a horse or other animal and pulled in the direction of the arrow *K* with the result that the links *E* and *G* will swing into position as shown in Figure 4 so that the rope as it leads on to the rope pulley

D passes between the roller H and one of the rollers F and is gripped with sufficient pressure to ensure the loop of the rope I securing a good friction engagement with 5 the said pulley D and cause the same to be operated.

When the rope I has been pulled out to its fullest extent the draught gear of the horse or other animal is connected to the 10 opposite end thereof and the said rope is again pulled outwardly.

The movement of the rope I causes the rope pulley D to be rotated and the links A to be operated to oscillate the operating lever to actuate the winch. The spindle of 15 the pulley D can be driven by a train of toothed gearing or by any other suitable mechanism from a motor attached to the frame of the winch or located in any convenient position.

In the modified form of the invention shown in Figure 6 of the drawings the hauling rope t is connected at one end to the lever and passes therefrom to and around 25 a pulley u' connected to a load rope x' and thence to a winding drum. With this form of the invention a constant hauling movement is applied to the load on both the backward and forward movements of the operating lever.

In operation the frame of the winch is anchored to a stump as shown in Figure 1 or to any other fixed object and the load rope x is connected to the tree or other object to be moved. The pawls h and l are then placed in their inoperative positions and the hauling rope t is fleeted through the snatch blocks u and v and around the winding drum b to place the first snatch block 35 adjacent to the hook r or the adjustable gripping device s. After the parts are placed in the positions above described the free end of the rope t is drawn taut and secured to the hook r or to the adjustable gripping device s and the pawls h and l are 40 released to permit of them returning to the operative positions when the hauling device may be put into operation.

The normal movement of the operating lever is indicated by the sector shown in 50 dotted lines in Figure 1 and when the lever is moving on its forward stroke the winding drum, rope and snatch blocks move in the directions indicated by the arrows shown in full lines and when the said lever is moving in the reverse or backward direction the rope and snatch blocks are moved in the direction indicated by the arrows shown in dotted lines.

On the forward movement of the operating lever the winding drum is rotated and the hauling rope is drawn around the second 55 snatch block v on to and pays off the opposite side of the winding drum so that the first snatch block u is drawn away from the

winch and consequent upon the extension of the loop in that part of the rope passing around the first snatch block a movement is applied to the load.

When the lever is moved forward the links 70 q also move forward and the end of the hauling rope connected thereto is allowed to move forward a lesser distance than that part of the rope leading on to and from the winding drum with the result that a 75 differential movement or leverage is applied to the hauling rope.

When the operating lever is moved in the reverse or backward direction the winding drum is held stationary by means of the retaining pawls l until the lever is thrust forward on its next stroke. The rearward movement of the lever causes the hauling rope to be drawn around the first snatch block and around the second snatch block 80 85 in the direction indicated by the arrows shown in dotted lines and a further movement to be applied to the load. When the lever is moving rearwardly a direct leverage is exerted on the hauling rope and the 90 loops in the rope passing around the first and second snatch blocks are shortened.

When the hauling rope is laid out as shown in Figure 1 of the drawings and the lever operated on its forward movement as 95 above described the first snatch block u will move toward the load a distance equal to three fourths of the distance the rope is paid on to the winding drum and the second snatch block v will move toward the winch 100 one eighth of the said distance the rope is paid on to the winding drum.

On the reverse or backward movement of the operating lever the first snatch block u is moved toward the winch a distance equal 105 to one half the distance of the movement of the hook r or gripping device s and the second snatch block v moves toward the winch a distance equal to one half the movement 110 of the first snatch block.

When a given load tension is applied constantly to the load rope there is greater friction on the parts of the device when the operating lever is thrust forwardly than when it is thrust rearwardly owing to the 115 winding drum operating on the forward stroke and remaining stationary on the reverse stroke.

In practice it has been found necessary to place the pivot point of the links q connecting the hook r or gripping device to the operating lever at a distance from the axle a slightly greater than one half the radius of the pitch line of the rope groove e in the winding drum so as to counterbalance the 120 extra friction resulting on the forward movement of the lever and to ensure the said lever operating with the application of a given power in both directions.

When the device has been operated to 130

draw the snatch blocks close to each other the hauling rope is detached from the hook or "grab" and the pawls *h* and *l* are released to permit of the hauling rope being fleeted to place the snatch blocks in their original positions and when the hauling rope is attached to the said hook or grab the device can be operated to impart a further movement to the load.

10 When the liner in the rope groove of the winding drum becomes worn and the mechanical efficiency of the device reduced and coefficient of friction between the surface of the winding drum and the rope may not be sufficient to ensure the rope gripping the drum with sufficient force to carry the strain due to the load.

15 In Figure 5 is illustrated a simple device for applying a new liner to the groove *e* of the winding drum. The device consists of a strap *L* of leather or other suitable material having a ring or loop *M* at one end and this strap is passed around the winding drum as shown in Figure 5 with the loop *M* at the highermost point and drawn tight when molten lead or soft alloy or other suitable material is poured through the loop. The molten lead or other material passes around the bottom of the rope groove and fills the space enclosed by the strap and when the metal has cooled the strap is removed and any rough edges or lumps on the liner is removed by the aid of any suitable tool.

20 30 35 In order to ensure the liner obtaining a good seating in the rope groove of the winding drum the sides and or bottom of the said groove can be provided with a plurality of shallow recesses *N* as shown in Figure 5 of the drawings or with flat portions (not shown).

40 45 For the purpose of convenience in the description of this invention certain terms have been employed which it will be understood are intended to be read as embracing their equivalents.

50 In this specification:—

The term "rope" is intended to include any other suitable flexible member such as a chain, cable, belt or the like, and vice versa.

55 The term "winch" is intended to include any rotatable drum, barrel, pulley, sheave or the like and vice-versa.

The term "snatch block" is intended to include a pulley, sheave, bollard or any other device around which a rope is adapted to pass freely.

60 65 In the operation of a hauling device constructed according to this invention the position of the load and the anchorage may be transposed and it will be clear that in the foregoing description where it is stated that one member or part of a member is connected to a load and the other member or part of a member is connected to an anchorage

the same effect may be obtained by transposing said load and anchorage and that the said terms are therefore transposable.

I claim:

1. A hauling and straining device comprising a winch having a winding drum, a pivoted operating lever and pawl and ratchet mechanism for intermittently rotating the winding drum, snatch blocks, a hauling rope looped to pass around the snatch blocks and the winding drum, one end of the said hauling rope connected to the lever and the opposite end to one of the snatch blocks, and means for attaching a load to the snatch block in the loop of the hauling rope and the winch to an anchorage, constructed and arranged whereby each of the backward and forward movements of the lever actuates the device to impart a strain to the hauling rope and a movement to a load attached thereto. 70 75 80 85

2. A hauling and straining device comprising a winch having a winding drum, a pivoted lever and pawl and ratchet mechanism for operating the winding drum, a snatch block, a hauling rope having one end connected to the said lever and looped to pass around the snatch block and then passed on to the said winding drum, and connections between the winding drum and 90 95 an anchorage and between the snatch block and a load.

3. A hauling and straining device comprising a winch having a winding drum provided with ratchet teeth, an operating lever pivoted to the winch, pawls on the lever engaging the ratchet teeth on the winding drum, retaining pawls pivoted to the frame of the winch, a grab connected to the lever at a distance from the pivot point 100 105 thereof less than the radius of the winding drum, a pair of snatch blocks, a hauling rope connected to the frame of one snatch block and looped around the second snatch block the winding drum and first snatch 110 block and having its opposite end adjustably connected to the grab and anchor and load ropes connected to the winch and to the second snatch block, substantially as described. 115

4. A hauling and straining device comprising a winch having a winding drum provided with ratchet teeth, an operating lever pivoted to the winch, pawls on the lever engaging the ratchet teeth on the winding drum, retaining pawls on the winch frame engaging the ratchet teeth, a hauling rope having one end connected to the lever at a distance from the pivot point thereof less than the radius of the winding drum 120 125 and passing to the said winding drum, a snatch block in a loop formed in the rope between the lever and the winding drum, and means for connecting a load to the snatch block. 130

5. In a hauling and straining device, a winding drum, an oscillating lever and mechanism for partially rotating the winding drum on one stroke of the lever, snatch blocks, a hauling rope having loops formed therein and passing around the winding drum and the snatch blocks and means for connecting one end of the hauling rope to the lever at a distance from the pivot point thereof less than the radius of the winding drum.

6. In a hauling and straining device, a winch having a winding drum provided with ratchet teeth, a lever pivoted to the spindle of the winding drum, spring actuated pawls on the lever arranged to engage the ratchet teeth, spring actuated retaining pawls on the winch adapted to engage the ratchet teeth, means for retaining the pawls out of engagement with the ratchet teeth on the winding drum, a hauling rope, and means for connecting one end of the

hauling rope to the lever at a distance from the pivot point thereof equal to approximately one half of the radius of the said winding drum. 25

7. In a hauling and straining device as claimed in claim 6, a winding drum having a rope groove therein provided with a liner of soft metal, such as lead as and for 30 the purpose set forth.

8. In a hauling and straining device as claimed in claim 1 a winding drum having a rope groove provided with inclined sides, a liner of soft metal in the bottom of the 35 rope groove, and recesses in the rope groove for firmly retaining the liner, substantially as described.

In testimony whereof he has affixed his signature in the presence of two witnesses. 40

ALFRED ARTHUR QUICK.
